UNITED STATES PATENT OFFICE.

J. EDMUND TONNELIER, OF PITTSBURGH, PENNSYLVANIA, ASSIGNOR TO JONES & LAUGHLIN STEEL CORPORATION, OF PITTSBURGH, PENNSYLVANIA, A CORPORATION OF PENNSYLVANIA.

FABRICATED STRUCTURAL MEMBER.

Application filed April 8, 1924. Serial No. 705,078.

To all whom it may concern:

Be it known that I, J. EDMUND TONNELIER, a citizen of the United States, residing at Pittsburgh, in the county of Allegheny and State of Pennsylvania, have invented an Improvement in Fabricated Structural Members, of which the following description, in connection with the accompanying drawings, is a specification, like characters 10 on the drawings representing like parts.

My invention aims to strengthen and improve rolled structural members or "shapes" of open web or trussed form, and to enable such members to be readily and economically 15 fabricated and utilized for building and other purposes.

In the accompanying drawings, wherein I have shown one embodiment of my invention for purposes of illustration,—

20 Fig. 1 is a side view of a trussed web I-beam such as is suitable for floor beams, roof trusses and purlins, bridge girders, and other structural purposes, strengthened at the ends by bracing members;

25 Fig. 2 is an enlarged side view of one end of the beam shown in Fig. 1;

Fig. 3 is a cross-section of the same on the line 3—3 in Fig. 2;

30 Fig. 4 is a top view of the end portion of the beam, Figs. 2, 3 and 4 being drawn to the same scale; and

Fig. 5 is a view similar to Fig. 3 in part, drawn to a larger scale and showing one manner of securing the bracing members by 35 suitable clips.

The invention may be applied to I-beams, channels, Z-sections, T-sections, H-sections, and other flanged shapes having trussed or open web portions formed integrally with 40 the flanges or margins. In rolling such structural shapes the web portions (which may be in the form of tie members) are most readily made of uniform strength and are equally spaced lengthwise of the shape.

45 Such structural shapes, if loaded to their maximum carrying capacity, are likely to collapse at their ends where they are supported unless the ends are braced in such a manner as to reinforce the adjacent ties

against failure from overloading. The 50 same applies to intermediate points where they may be called upon to support concentrated loads, as for example, at the points of support of a beam. In such and many other cases, provision may advantageously be 55 made to prevent collapse of the shape at unsupported or highly stressed points by additional bracing for the flanges and web portions capable of resisting bending and shearing forces.

60 The particular embodiment of the invention selected for illustration herein and shown in the drawings comprises a principal member and stiffeners, more especially such as are adapted for reenforcing the ends of 65 lattice-web structural shapes, although they may be applied to intermediate points. Other shapes and forms of stiffeners are contemplated.

65 Referring particularly to Fig. 1, the invention is embodied in a trussed I-beam having flanges 12 connected by angularly disposed lattice or web members 13 formed integrally with the flanges by any suitable process of manufacture. Each end of the 70 beam is strengthened by securing thereto suitable stiffeners or reenforcement, such as the flanged hollow T-plates 14, which may be pressed from sheet metal and are preferably disposed astride of the flanges and 75 engaging thereunder and on opposite sides of the web members of the beam at its ends. Preferably the outer ends of the hollow T-plates project beyond the ends of the beam 80 and are pressed together and spot welded 85 or otherwise secured so as to prevent telescoping them too far over the end portions of the beam as hereinafter described, and to give them additional strength in resisting possible torsional stresses.

90 Intermediate points may be likewise strengthened by similar plates spanning the space between two or more panel points, i. e., points at which the web members intersect the top and bottom flanges or chord members, and may be disposed upon either or both of the beam flanges, with their horizontal legs 15 out-turned, whereby they lend 95

themselves readily for the support or attachment of other portions of a building or structure.

The preferred manner of securing the T-plates to the web portions of the beam is by clips 16, which embrace the horizontal legs 15 and are bent over the edges of the latter to hold them in place, as shown in Fig. 3; although any suitable means for attaching the members together may be used, such as by spot welding, or by bolts 17, as shown in Figs. 2, 3, and 4, for which spaced holes 18 are advantageously provided in the T-plates to permit of their application to suit any length of beam or spacing of web members. The clips 16 are preferably shaped so that they may be applied in the field with a hammer or other suitable tool, as illustrated in Fig. 5, thereby permitting the beams to be cut to length and end or intermediate stiffeners attached at the place of use without requiring expensive equipment for this purpose.

The horizontal legs of the plates 14 afford wide supports for the ends of the beam and may be punched with holes 19 for securing them to the supporting structure by bolts, rivets or other usual standard forms of construction; and similarly they may be utilized to support minor portions of the floor system or other parts of the structure. Any free end portions of incomplete tie members at the ends of the beam may advantageously be removed to avoid interference with portions of the supporting structure.

The stiffener members not only strengthen the ends and critical points of the beam or other element to enable it to carry its maximum load with safety, but enable standard forms of connections with other portions of the structure to be utilized, which could not otherwise be connected to the narrow flanges and light tie members characteristic of beams of the open web type. The end supports afforded by the T-plates are wide and are located preferably above the central axis of the beam, thereby enabling such members to be placed in position for use without temporary bracing to secure them against overturning during erection of the structure. A further advantage is that (within the limits of the projecting ends of the angle bars) the ends of the beam and strengthening members may be cut off to reduce its length or suit the conditions of use without weakening the beam, as with solid web beams.

The invention is not restricted to the forms, shape and dimensions of the members shown in the drawings, as it is obvious that it may be applied in various forms and shapes suitable to the uses for which it is adapted.

What I claim as my invention and desire to secure by Letters Patent is:

1. A rolled shape having an open work web connecting top and bottom flanges and strengthened by longitudinally extending formed plates embracing a flange and secured in place by means passing through the openings in the web.

2. A rolled shape of the character described having marginal flanges and a web integral therewith but separated to form connecting tie members, and a self supporting strengthening member embracing a flange and secured to said shape on opposite sides of its web.

3. A rolled shape having flanges connected by tie members integral therewith forming panels, and formed plates telescoped upon said flanges and spanning one or more panels.

4. A rolled shape having flanges connected by tie members integral therewith forming panels, and hollow end plates disposed in alignment with one of said flanges and embracing its opposite sides, and clamping means for securing said end plates to the adjacent tie members.

5. A rolled shape having an open work web comprising integral tie members, and lengthwise extending braces enclosing the upper edge of the shape and clamped to the upper ends of adjacent tie members.

6. A rolled shape having marginal flanges and an open-work web comprising integral tie members connecting said flanges at spaced points forming panels, and lengthwise extending braces embracing portions of said flanges and the ends of adjacent tie members and having a length greater than the space between adjacent tie members so as to span more than one panel, and securing clips for said braces positioned in openings between said tie members and having portions adapted to be bent around the edges of said braces.

7. A rolled shape having an open-work web and continuous top and bottom flanges, and self-positioning braces seated upon one of said flanges at its ends and secured to said shape by clips positioned in openings in said web.

8. A rolled shape having parallel flanges and a web comprising integral, diagonally disposed tie members, and lengthwise extending braces shaped to embrace one of said flanges telescoped over its ends and means cooperating with the adjacent tie members for securing said braces against lengthwise displacement, said braces having horizontally disposed portions constituting supports.

9. A rolled shape having parallel flanges and a web comprising integral, diagonally disposed tie members, and lengthwise ex-

tending braces shaped to embrace one of said flanges telescoped over its ends and means cooperating with the adjacent tie members for securing said braces against lengthwise displacement, said means being detachable for attaching and removing said braces to suit the conditions of use.

10. A rolled shape having top and bottom flanges 12 and an open-work web 13,

and provided with stiffeners 14 of hollow T-shape having out-turned legs 15 telescoped upon the ends of a flange 12 and secured in place by clips 16 passing through openings in the web and embracing the outer edges of the legs.

In testimony whereof, I have signed my name to this specification.

J. EDMUND TONNELIER.
